CLAIM

I claim the ornamental design for an electrical interface, as shown and described.

DESCRIPTION

FIG. 1 is a right rear top perspective view of an electrical interface.

FIG. 2 is an enlarged view of the electrical interface shown in FIG. 1.

FIG. 3 is a left top front perspective view of the electrical interface shown in FIG. 2.

FIG. 4 is a right top front perspective view of the electrical interface shown in FIG. 2.

FIG. 5 is a left side view of the electrical interface shown in FIG. 2.

FIG. 6 is a right side view of the electrical interface shown in FIG. 2.

FIG. 7 is a front view of the electrical interface shown in FIG. 2; and,

FIG. 8 is a top view of the electrical interface shown in FIG. 2.

The broken lines represent portions of the electrical interface that form no part of the claimed design. The uneven broken lines represent boundaries of the design and form no part of the claimed design.
